ADJUSTABLE WRENCH

Edward H. Luckey, Kansas City, Mo.

Application October 6, 1936, Serial No. 104,320

1 Claim. (Cl. 81—111)

The invention relates to a wrench and more especially to an adjustable open end wrench.

The primary object of the invention is the provision of a wrench of this character, wherein the same can be manipulated in small spaces and also the wrench may be adjusted with dispatch and in a novel manner.

Another object of the invention is the provision of a wrench of this character, wherein on adjustment thereof the same will be maintained in its adjusted position and the adjustment is accomplished with ease and dispatch.

A further object of the invention is the provision of a wrench of this character, which is extremely simple in construction, thoroughly reliable and effective in its operation, strong, durable, easy of adjustment, enabling minute adjustment, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claim hereunto appended.

In the accompanying drawing:

Figure 1 is a plan view of a wrench constructed in accordance with the invention.

Figure 2 is a plan view of one of the elements 30 of the wrench.

Figure 3 is an edge elevation of the wrench.

Figure 4 is a vertical longitudinal sectional view through the wrench.

Figure 5 is a sectional view on the line 5—5 of Figure 1 looking in the direction of the arrows.

Figure 6 is a fragmentary vertical longitudinal sectional view through the wrench showing the elements separated under a confined spring therebetween for easy adjustment.

Similar reference characters indicate corresponding parts throughout the several views in the drawing.

Referring to the drawing in detail, the wrench comprises a pair of lever elements 10 and 11, respectively, these being cut into for a major distance of their length at confronting sides to line and have register a pair of jaws 12, the jaw of either element being located at the outer longitudinal edge thereof and is formed with a spaced serrated working or gripping face 13. The end of each lever element 10 and 11 carrying the jaw 12 is relatively wide as at 14 and this widened portion is formed with an arcuate slot 15 transversely disposed therein.

Remote from the wider ends 14 of the lever elements 10 and 11 and in the inner faces there-

of are cavities 16 for accommodating and confining a substantially U-shaped wire spring 17, it having in its tines bights 18 for distorting such tines so as to effect a spreading apart of the elements 10 and 11 and also that such tines will swing the said elements 10 and 11 to laterally spread the jaws 12 from each other, the swinging of the elements being on an axis constituted by a pivot bolt 19 passed transversely through the elements next to the ends thereof remote from 10 the enlarged ends 14.

Passed through the slots 15 is a nut carrying bolt 20 while 21 is the tail nut threaded upon this bolt 20. Through the use of the nut carrying bolt 20 the lever elements 10 and 11 can be 15 locked or made fast when adjusted relative to each other.

The wider ends 14 of the elements 10 and 11 immediately inwardly of the jaws 12 thereon and upon confronting faces have interlocking teeth or ribs 22 so that when the nut carrying bolt 20 fastens the elements 10 and 11 in adjusted position these teeth or ribs 22 interlock with each other and thus firmly holding the elements adjusted.

It will be apparent from the figures in the drawing that when the bolt 20 is loosened the spring 17, which is trained about the pivot 19 within the cavities 16, becomes active for separating the elements 10 and 11 and in lateral direction and at right angles thereto so that the jaws 12 will automatically open. By pressing against the elements 10 and 11 when the bolt 20 is loosened against the resistance of the spring 17 the jaws 12 can be brought to the required distance apart according to the work to be operated upon and by tightening the bolt 20 fastened in adjusted position. There is present sufficient clearance at the pivot 19 whereby the wrench elements 10 and 11 may separate and assume a position 40 as shown in Figure 6 of the drawing when the bolt 20 is loosened.

What is claimed is:

A wrench of the character described comprising levers each having a jaw at one end, a pivot 45 swingingly connecting the levers together, interlocking faces formed on said levers, means for interlocking the faces with each other, and a distorted double arm spring confined between the levers and active thereon in two directions at 50 right angles to each other for the simultaneous opening of the jaws and separating the interlocking faces from each other, said means including a tail nut carrying bolt, the levers at the interlocking faces being slotted for accommodating 55 said bolt.

EDWARD H. LUCKEY.
